UNITED STATES PATENT OFFICE.

LOUIS B. KETCHAM, OF BINGHAMTON, NEW YORK, ASSIGNOR TO UNION SPECIAL MACHINE COMPANY, OF CHICAGO, ILLINOIS, A CORPORATION OF ILLINOIS.

NEEDLE-GUARD FOR SEWING-MACHINES.

1,212,778.

Specification of Letters Patent. Patented Jan. 16, 1917.

Application filed May 14, 1913. Serial No. 767,703.

To all whom it may concern:

Be it known that I, LOUIS B. KETCHAM, a citizen of the United States, residing at Binghamton, in the county of Broome, State of New York, have invented certain new and useful Improvements in Needle-Guards for Sewing-Machines, of which the following is a description, reference being had to the accompanying drawing and to the figures of reference marked thereon.

The invention relates to new and useful improvements in needle guards for sewing machines, and more particularly to a needle guard which is movable into contact with the needle and prevents the deflection of the needle into the path of the looper.

An object of the invention is to provide a needle guard which is capable of being moved into contact with the needle, and of following the needle as it rises from the lower end of its stroke, so as to engage the needle at a point adjacent the eye thereof and maintain said engagement until the point of the looper has passed the needle.

A further object of the invention is to provide a needle guard which is positively moved continuously in a path substantially at right angles to the path of the looper, and which needle guard contacts with the needle during a portion of its travel for holding the needle properly positioned while the point of the looper is passing the same.

These and other objects will in part be obvious, and will in part be hereinafter more fully disclosed.

In the drawings, which show by way of illustration one embodiment of the invention, Figure 1 is a detail showing in front elevation a portion of the forward end of a sewing machine having my improvements applied thereto; Fig. 2 is a transverse sectional view, showing the needle guard, its supporting means, and its relation to the needle and feed; Fig. 3 is a detail in section, showing the adjustable connection between the needle guard and the supporting fork; Fig. 4 is a detail in plan, showing the needle guard, the feed dog, the needles and the loopers; Fig. 5 is a detail in perspective, showing the relation of the needle guard to the needles; Fig. 6 is a detail in perspective, showing the operating mechanism for the needle guard; Fig. 7 is a detail showing the relative positions of the needle guard

and the needle and the eccentric for operating the needle guard, when the needle is near the lower end of its stroke; Fig. 8 is a similar view, showing the needle positioned for the point of the looper to enter the needle loop; Fig. 9 is a similar view showing the needles substantially at the upper end of their stroke; Fig. 10 is a diagrammatic view, showing the relations of the needle guard, the needle and the work support, when the needle guard first contacts with the needle; Fig. 11 is a similar view, showing the needle at the lower end of its stroke; and Fig. 12 is a similar view, showing the needle positioned for the looper point to enter the needle loop.

The invention is shown applied to a sewing machine which consists of a supporting bed 1 having the usual work support and an overhanging arm 2, in which reciprocates a needle bar 3. This needle bar is connected by a link 4 to the usual needle lever 5. As herein shown, the needle bar is provided with two pairs of needles 8 and 9. The needles 8 are arranged in rear of the needles 9. A looper 10 cooperates with the two needles 8, and a looper 11 cooperates with the two needles 9. Each pair of needles is set in a line substantially at right angles to the line of feed, and, therefore, the single looper which cooperates with the two needles may pass through or into both of the needle loops, one after the other. The loopers 10 and 11 are mounted on a looper carrier 12, which is pivoted at 13 to a looper support 14. This looper support 14 is rocked, so as to move the loopers 10 and 11 in a direction substantially parallel with the line of feed, and thus impart to the loopers the usual needle-avoiding movement. The looper carrier 12 is rocked on a pivotal support 13, by a link 15, and this link moves the loopers into and out of the needle loops in the well known manner.

The fabric is presented to the needles by a feed dog 16, carried by a feed bar 17, which is pivoted to a feed rocker 18. The usual eccentric engages the feed bar and raises and lowers the same, while the feed dog is moved back and forth by a connection 19 between the feed rocker 18 and the forward end of the main shaft.

It is well known that the needles during the setting of the stitch and the feeding of the fabric are under strain in a direction par-

- allel with the line of feed, and this strain is liable to deflect the needles so that the loopers which move in rear of the needles as they enter the needle loops may strike the needles.
- 5 The invention is directed to a needle guard which engages the needles, prevents any rearward deflection of the same and holds the needles properly positioned for the passing of the looper. My improved needle 10 guard consists of a supporting shank 20, which carries a laterally projecting finger 21, the front upper face of which is inclined, so as to form a needle-guiding shoulder 22. This needle-guiding shoulder is the needle 15 guard for the needles 8. The shank is also provided with an inclined face 23, which forms a needle-guiding shoulder 24, and this needle-guiding shoulder 24 is the needle guard for the needles 9.
- 20 The supporting shank 20 is attached to a bracket 25 by a suitable screw 26. The bracket 25 is turned upward at its front end and formed with a groove which receives a rib 27 on the slotted shank of the needle 25 guard, and the upturned portion of the bracket 25 is slotted, so that said shank may be adjusted vertically on the bracket. This bracket 25 is provided with two slots 28 and 29. The bracket is secured to a supporting 30 fork 30 by screws 31, which pass through the slots 28 and 29 into the fork. These slots are elongated, so the bracket 25 may be adjusted lengthwise on the supporting fork. The supporting fork 30 is pivoted at 32 to 35 a supporting arm 33, which in turn is pivoted on the pivot pin 34, for the feed rocker 18. This arm 33 turns freely on the pivot pin 34, and serves merely as a guide and support for the rear end of the needle guide 40 supporting fork. An eccentric 35 is attached to the main shaft 36. The supporting fork 30 extends above and below said eccentric 35, and is provided with suitable hardened wearing plates 37, which engage 45 the eccentric. A bar 38 extends across the inner portion of the supporting fork 30, and is screwed thereto. Said bar is provided with a laterally projecting portion 39, which engages the eccentric 35 at the rear side 50 thereof. The second bar 40 is attached to the fork by suitable screws 41, and this bar is also provided with a laterally projecting member 42, which engages the eccentric 35 at the front side thereof. It will be apparent, 55 therefore, that the eccentric turns between the members 39 and 42, and the hardened plates 37, so said eccentric is engaged on four sides thereof, and, therefore, the supporting fork 30 will positively follow said eccentric as it rotates, and all movements imparted to the supporting fork both back and forth and up and down, will be positive. As 60 this eccentric rotates, the supporting fork will, therefore, be raised and lowered at its 65 front end, swinging about the pivot pin 32,

and said supporting fork will also be moved bodily back and forth, swinging the arm 33 about the pivot pin 34.

In describing the operation of my device, I will refer to a single needle guard, it being obvious that both needle guards operate in precisely the same manner in connection with the respective needles. The eccentric 35 is so timed that when the needles are descending, and are nearly to the lower end of their stroke, said eccentric is positioned as shown in Fig. 7, with the supporting fork lowered to its extreme lower position. As the needles continue their downward movement, the eccentric turning in the direction of the arrow will move the supporting fork forward, bringing the needle guard into contact with the needle. The needle guard is so positioned as to engage the needle adjacent the eye therein. As the needle starts on its upward movement, the eccentric continuing its motion in the direction of the arrow, will cause said supporting fork to move upward, and the needle guard will follow the needle in its upward travel. When the eccentric 90 has reached the position shown in Fig. 8, the looper is moved forward, and is about to enter the needle loop, and the needle at this time is held properly positioned by the needle guard, so that the looper cannot by 95 any possibility strike the needle. A further upward movement of the needle carries the needle away from the needle guard, the eccentric continues to lift the supporting fork for the needle guard, but the further movements of the needle guard are idle movements, so far as the needle is concerned, until the eccentric brings the needle guard into the position shown in Fig. 9.

In Figs. 10, 11 and 12, I have shown diagrammatically the travel of the needle and the needle guard relative to the work support. In Fig. 10 the needle guard first contacts with the needle, and the eccentric at this time for operating the needle guard, is positioned as shown in Fig. 9. In Fig. 11 the needle has reached the lower end of its stroke, and the needle guard has continued its forward movement, the needle being slightly deflected to permit this forward movement of the needle guard, and the needle guard has also raised slightly from the position shown in Fig. 10. In Fig. 12 the needle guard has raised farther, following the needle in its upward path, although the travel of the needle is slightly faster than that of the needle guard. When the needle guard is positioned as shown in this figure, the point of the looper is entering the needle loop, and the needle guard has finished its function as a needle guard, and may be moved away from the needle.

Inasmuch as the needle guard engages the needle at a point adjacent the eye or point thereof, the slight spring of the needle 130

through the movement of the needle guard, has no ill effect upon the needle, and the needle is firmly engaged and positively held out of the path of the looper.

- 5 It will be noted from the above description that the needle guard moves continuously in a plane substantially at right angles to the path of travel of the looper, into and out of the needle loop, and that during a portion 10 of the travel of the needle guard, it is in contact with the needle. It will also be noted that the needle guard which engages the needle and positions the same, is positively moved into and out of contact with 15 the needle, which especially adapts the same for use in high speed machines.

While I have described my invention as applied to a machine having a plurality of loopers and a plurality of pairs of needles, 20 it will be obvious from certain aspects of the invention, that the needle guard may be used in connection with a single needle. When a plurality of loopers are used, as above described, it is also desirable to provide 25 means for preventing the rear pair of needles from being bent or deflected forwardly into the path of the front looper. The shank 20 is also provided with a laterally projecting finger 43, which is spaced 30 from the finger 21, and which is so positioned that the needles 8 pass between said finger 21 and the finger 43. The rear face of this finger 43 is rounded, so that if the needles are slightly deflected toward the 35 front of the machine, they will engage said rounded face and be moved into proper position to allow the looper 11 to clear the needles as it moves forward into the needle loops thrown out by the needles 9.

- 40 It will be apparent from the above description, that the supporting shank for the needle-guiding shoulders may be adjusted both vertically and laterally of the needle path, so that said guiding shoulders may be 45 properly positioned to coöperate with the needles.

It will be noted from Fig. 4 of the drawings that the looper 11 is provided with the usual needle guard 11^a, which is set slightly 50 in advance thereof. This needle guard will move in front of the needles 9, 9 as the looper is approaching the inner loops thrown out by these needles, and, as a consequence, said needle guard will prevent the deflection of 55 the needles toward the front of the machine, while the needle guard 24 will prevent the deflection of said needles toward the rear of the machine. The same is true respectively of the needle guards 22 and 21 relative 60 to the needles 8, 8.

It is obvious many minor changes in the details of the construction and arrangement of the parts may be made, without departing from the spirit of the invention, 65 as set forth in the appended claims.

Having thus described my invention, what I claim as new and desire to secure by Letters Patent, is:—

1. The combination with stitch-forming mechanism including a vertically reciprocating needle and a looper coöperating therewith, of a needle guard, and means for moving the needle guard into contact with the needle and upwardly with the needle while in contact therewith, whereby said needle is held in proper position relative to the looper as the looper enters the needle loop. 70

2. The combination with stitch-forming mechanism including a needle and a looper coöperating therewith, of a needle guard, a supporting fork therefor, an eccentric, means carried by the fork and engaging said eccentric, whereby said fork is positively moved back and forth and up and down, said needle guard being adapted to engage the needle and move therewith, so as to properly hold the needle in position for the passing of the loop. 80

3. The combination with stitch-forming mechanism including a needle and a looper coöperating therewith, of a needle guard, a supporting fork therefor, an eccentric, means carried by the fork and engaging said eccentric, whereby said fork is positively moved back and forth and up and down, said needle guard being adapted to engage the needle and move therewith, so as to properly hold the needle in position for the passing of the loop, and means 100 whereby said needle guard may be adjustably attached to its supporting fork. 95

4. The combination with stitch-forming mechanism including a needle and a looper coöperating therewith, of a needle guard, a supporting fork therefor, means for pivotally supporting the rear end of said fork, an eccentric engaging the front end of said fork for moving said fork up and down and back and forth, said needle guard being 110 adapted to engage and move with the needle for holding the same in position for the passing of the looper. 105

5. The combination with stitch-forming mechanism including a needle and a looper coöperating therewith, of a needle guard, a supporting fork therefor, means for pivotally supporting the rear end of said fork, an eccentric engaging the front end of said fork for moving said fork up and down and back and forth, said needle guard being 115 adapted to engage and move with the needle for holding the same in position for the passing of the looper, and means whereby said needle guard may be attached to said supporting fork, so that said needle guard may be adjusted vertically and also adjusted transversely of the path of travel of the looper. 120

6. The combination with stitch-forming 130

mechanism including a plurality of pairs of needles, each pair being arranged in a different vertical plane extending transversely of the line of feed, a looper for each pair 5 of needles, a needle guard for each pair of needles, a supporting shank for the needle guards, and means for moving said shank, whereby said needle guards are caused to contact with the needles and move upwardly 10 with the needles for holding the needles in proper position for the loopers to enter the respective needle loops.

7. The combination with stitch-forming mechanism including a plurality of pairs of 15 needles, each pair being arranged in a different vertical plane extending transversely of the line of feed, a looper for each pair of needles, a needle guard for each pair of needles, a supporting shank for the needle 20 guards, means for moving said shank, whereby said needle guards are caused to contact with the needles and move upwardly with the needles for holding the needles in proper position for the loopers to enter the respective 25 needle loops, and means carried by said shank for preventing the rear pair of needles from being deflected forwardly into the path of the forward looper.

8. The combination with stitch-forming 30 mechanism including a plurality of pairs of needles, each pair being arranged in a different vertical plane extending transversely of the line of feed, a looper for each pair of needles, a needle guard for each pair of 35 needles, a supporting shank for the needle guards, a supporting fork for said shank, means for pivotally supporting the rear end of said supporting fork, an eccentric for engaging the forward end of said fork, means 40 carried by the fork and engaging said eccentric, whereby said fork is positively moved back and forth and up and down from said eccentric, said needle guard being so disposed as to engage the needles and move

upwardly therewith, whereby said needles 45 are properly held for the loopers to enter the respective needle loops.

9. The combination of a stitch forming mechanism including a needle, a looper co-operating therewith, a feeding mechanism 50 including a feed bar, means for giving the feed bar a rising and falling movement, a needle guard, and means for giving said needle guard both a back and forward and an up and down movement from the means 55 which raises and lowers the feed bar.

10. The combination of a stitch forming mechanism including a needle, a looper co-operating therewith, a feeding mechanism including a feed bar, means for giving the 60 feed bar a rising and falling movement, a needle guard, and means for giving said needle guard both a back and forward and an up and down movement from the means which raises and lowers the feed bar, said 65 upward movement of the needle guard being substantially in line with the needle and while in contact therewith.

11. The combination with stitch forming mechanism including a plurality of needles 70 arranged one in advance of the other, whereby said needles are disposed in different vertical planes extending transversely of the line of feed, a looper for each needle, a needle guard for each needle, and means for 75 moving the needle guards into contact with their respective needles and upwardly therewith whereby said needles are held in proper position relative to their respective loopers as the loopers enter their respective 80 needle loops.

In testimony whereof, I have affixed my signature, in the presence of two witnesses.

LOUIS B. KETCHAM.
